[57] CLAIM

The ornamental design for an agricultural chemical application vessel, as shown and described.

DESCRIPTION

FIG. 1 is a top plan view of an agricultural chemical application vessel showing my new design;

FIG. 2 is a left side elevational view thereof, the right side view being a mirror image of that shown;

FIG. 3 is a bottom plan view thereof;

FIG. 4 is a front elevational view thereof;

FIG. 5 is a rear elevational view thereof;

FIG. 6 is a top plan view thereof with the injection mechanism in the working position;

FIG. 7 is a left side elevational view of FIG. 6, the right side view being a mirror image of that shown;

FIG. 8 is a bottom plan view of FIG. 6;

FIG. 9 is a front elevational view of FIG. 6; and,

FIG. 10 is a rear elevational view of FIG. 6.
